DESIGN FOR A FASTENER PRONG CAP

Harold J. Reiter, Chicago, Ill.

Application September 18, 1940, Serial No. 95,182

Term of patent 14 years

To all whom it may concern:

Be it known that I, Harold J. Reiter, a citizen of the United States, residing at Chicago, in the county of Cook and State of Illinois, have invented a new, original, and ornamental Design for a Fastener Prong Cap, of which the following is a specification, reference being had to the accompanying drawing, forming a part thereof in which:

Fig. 1 is a plan view of a fastener prong cap showing my new design; and

Fig. 2 is a side elevational view thereof.

I claim:

The ornamental design for a fastener prong cap, substantially as shown.

HAROLD J. REITER.
